US00D685744S

(12) **United States Design Patent**
Kajiura et al.

(10) **Patent No.:** US D685,744 S
(45) **Date of Patent:** ** Jul. 9, 2013

(54) **ELECTRICAL TERMINAL**

(71) Applicants: **Motomu Kajiura**, Tokyo (JP);
Yasutoshi Kameda, Kisarazu (JP);
Jeffery Garvais, Beaverton, OR (US)

(72) Inventors: **Motomu Kajiura**, Tokyo (JP);
Yasutoshi Kameda, Kisarazu (JP);
Jeffery Garvais, Beaverton, OR (US)

(73) Assignees: **FCI**, Guyancourt (FR); **FCI Americas Technology LLC**, Carson City, NV (US)

(**) Term: **14 Years**

(21) Appl. No.: **29/437,750**

(22) Filed: **Nov. 20, 2012**

Related U.S. Application Data

(63) Continuation of application No. 29/393,270, filed on Jun. 1, 2011, now Pat. No. Des. 671,501.

(57) **CLAIM**

The ornamental design for an electrical terminal, as shown and described.

DESCRIPTION

The present application is related by subject matter to design patent applications entitled "Electrical Connector" filed on even date herewith under 29/393,276, "Electrical Connector" filed on even date herewith under 29/393,280, "Electrical Terminals for Electrical Connector" filed on even date herewith under 29/393,282, "Electrical Terminal" filed on even date herewith under 29/393,269, "Electrical Terminal" filed on even date herewith under 29/393,278, "Electrical Terminal" filed on even date herewith under 29/393,281, and "Electrical Terminal" filed on even date herewith under 29/393,283.

FIG. 1 is a top, right, front perspective view of an electrical terminal showing our new design;

FIG. 2 is a bottom, left, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line portion of the figure drawings is included to show unclaimed subject matter only and forms no part of the claimed design.
